UNITED STATES PATENT OFFICE.

PAUL PRIEM, OF HEIDENHEIM-ON-THE-BRENZ, GERMANY, ASSIGNOR TO AMERICAN VOITH CONTACT COMPANY, INC., OF NEW YORK, N. Y., A CORPORATION OF NEW YORK.

WOOD GRINDER.

Original application filed June 12, 1922, Serial No. 567,778. Divided and this application filed February 10, 1923. Serial No. 618,328.

To all whom it may concern:

Be it known that I, PAUL PRIEM, a citizen of the Republic of Germany, and residing at Heidenheim-on-the-Brenz, Germany, have 5 invented certain new and useful Improvements in Wood Grinders, of which the following is a specification.

The present invention relates to wood grinders, and particularly to feed devices for 10 advancing the wood blocks against the grind stone. The invention is particularly applicable to continuously operated wood grinders as distinguished from intermittently operating grinders, and the object of my 15 invention is to provide a mechanism which in operation increases the pressure of the feed devices upon the interior of the charge by increasing the lateral thrust of the feed devices as the latter approach the charge 20 toward the grind stone.

The present application is a division of my copending application Serial No. 567,- 778, filed June 12, 1922, and is directed to the particular construction illustrated in the 25 accompanying drawing, in which the figure illustrates in vertical section a grinder in which my invention is embodied in a single specific form.

As pointed out in my copending application above mentioned, the devices in common use, prior to my invention, for continuously operating presses have commonly been of a type in which the charge in the hopper is advanced against the stone by means of 35 feed chains provided with cross bars which travel upon the opposite inner faces of the hopper and engage the sides of the charge of wood blocks which are thus advanced toward the grind stone. In this type of construction the chains move in a substantially parallel direction and do not press the blocks in the hopper as they advance toward the stone, the result being that the effort of the feed chains is exerted with greater effect at 40 the sides of the charge than upon the mid portions of the latter. The present invention provides a feed device in which the charge is laterally compacted by the feed devices as the charge approaches the stone, the lateral 45 thrust exerted being sufficient to exert enough pressure to advance the charge throughout its area with substantially uniform pressure at all points against the stone. Various ways of accomplishing this are illustrated in my copending application above 55

mentioned, and the present application is confined to a single specific form of construction therein illustrated which has been found to be efficient in practice.

As indicated in the drawing, the structure 60 comprises a pair of spaced standards 1, in which is journaled a shaft 2 carrying the grind stone 3. Above the latter is the hopper 4, through which the wood blocks are led to the stone. Between the standards 1, 65 adjacent the stone, extend transverse vertical plates 5. Travelling over the plates 5 are feed devices in the form of wedge blocks 6 carried by endless chains 7 which pass over upper and lower sprockets 8 and 9, one 70 sprocket of each pair being driven from any suitable source of power. The wedge blocks are pivotally connected to the chains so that they may change their angular position through any appropriate arc. 75

In operation the wedge blocks gradually vary their inclination from a downwardly inclined position to a position more nearly horizontal. Thus, if the wedge blocks at the outset of their working travel assume an angle of 60 degrees from the horizontal, their speed of advance may be so much greater with respect to the speed of consumption of the charge by the stone, that as the wedge blocks approach the stone they assume an 80 angle of only from 30 to 45 degrees. It is obvious that this change in angular position of the wedge blocks exerts a lateral compression of the charge as it approaches the stone, so that a simultaneous forward feed 85 and lateral compression of the charge takes place. The effective result is a substantially uniform thrust of the charge throughout its entire working area against the stone. The extent of angular variation of the wedge 90 blocks during their working travel may of course be varied by varying the speed of drive of the carrying chains, and may be varied in accordance with the nature of the wood which forms the charge. 95

Having thus described an appropriate embodiment of the underlying thoughts which I claim as my invention—

I claim:

1. In a wood grinder, a grind stone, an 105 associated hopper for a charge of wood blocks, and means engaging a side of the charge for forcibly feeding the latter against the grind stone, said means comprising an endless carrier rotating continuously in one 110

- direction and thrust blocks mounted thereon and engaging a side of the charge, and serving by variation of inclination as they approach the stone to compact the charge.
5. 2. A feed device for wood grinders or the like, comprising a receptacle through which a charge may pass, and means for advancing the charge through said receptacle, said means comprising an endless carrier, wedge blocks pivoted thereon and adapted to engage the charge, and means for driving the carrier constantly in one direction and at a speed in excess of the advance of the charge whereby the angular position of the wedge blocks with respect to the charge is varied.
10. 3. A feed device for wood grinders or the like, comprising a receptacle through which a charge may pass, and means for advancing the charge through said receptacle, said means comprising a pair of endless carriers arranged on opposite sides of the charge, and a series of wedge blocks arranged on said carriers and engaging opposite sides of the charge, together with means for driving said carriers constantly in one direction and at a speed in excess of the advance of the charge to cause the wedge blocks to gradually approach each other, and thus to compact the charge between the same.
15. 4. In a feed device for wood grinders or the like, a series of wedge blocks arranged on opposite sides of the charge, carriers on which said wedge blocks are pivoted, means for advancing the carriers constantly in one direction and at substantially uniform speed in excess of the feed of the charge, together with supports against which said blocks exert their thrust during their work travel.
20. 5. In a wood grinder, a hopper in which the charge comprises a series of billets, the longitudinal axes of which are substantially parallel and horizontal, and a feed device arranged at a side of the hopper which is substantially parallel to the longitudinal axes of the billets, said feed device comprising members advancing toward the stone and shaped to impart both a forward feed thrust and also a lateral compacting thrust to the billets constituting the charge as the latter approaches the stone.
25. 6. In a wood grinder, a hopper in which the charge comprises a series of billets, the longitudinal axes of which are substantially parallel and horizontal, and a feed device arranged at a side of the hopper which is substantially parallel to the longitudinal axes of the billets, said feed devices comprising members advancing toward the stone, and changing position with respect to the charge as they approach the stone to effect a forward feed and a lateral compacting effort upon the billets constituting the charge as the latter approaches the stone.
30. 7. The method of feeding a charge in a wood grinder or the like, which consists in applying to the charge a feed thrust to advance the charge, and converting at least portion of said feed thrust into a lateral compacting thrust as the charge advances.
35. In testimony whereof I have signed my name to this specification.

PAUL PRIEM.
